E. S. NIESTRADT

APPARATUS FOR MAKING MOLDS FOR BUILDING BLOCKS

Patented July 24, 1928.

1,678,267

UNITED STATES PATENT OFFICE.

ERNEST S. NIESTRAUDT, OF DENVER, COLORADO, ASSIGNOR TO THE NORTHWESTERN TERRA COTTA COMPANY, OF CHICAGO, ILLINOIS, A CORPORATION OF ILLINOIS.

APPARATUS FOR MAKING MOLDS FOR BUILDING BLOCKS.

Application filed June 14, 1927. Serial No. 198,723.

My invention relates to apparatus for making molds used in the manufacture of building blocks of plastic materials, and more particularly to certain new and useful 5 improvements in the apparatus shown and described in my application for patent Serial No. 138,233, filed September 28, 1926.

The molds made by means of the apparatus as disclosed in the above described 10 application for patent, consist of a base member, two side members and two end members, separately formed of plaster of Paris or other plastic material. The side members are cast in knockdown molds preferably made of metal and assembled upon a table or a work bench, and the base member or matrix member is made of a mass of soft plaster of Paris or the like on a work bench or slab, by drawing a profile templet 15 across the surface thereon.

The end members of the mold are produced in forms of which the base and side members assembled in their relative positions for casting the building blocks, are 20 parts.

It is with the method of forming the end blocks that the present invention is directly concerned. The several members of the 25 mold are connected by V-shaped tongues and grooves at their adjoining sides and edges, but the side and end members are otherwise loosely supported on the base member.

In producing the end members as stated 30 hereinbefore, the side members are placed upon the base member and other devices hereinafter to be described are positioned so as to cooperate with the end portions of the base and side members to form molds in 35 which the end members are cast.

The grooves and tongues which connect the side members with the base are not sufficient to hold the side members against lateral displacement while the casts of the 40 end pieces are being made, with the result that unless locking means be provided to insure the rigidity of the side members, the expansion of the plastic material used in making the end pieces may cause the side members to move outwardly with the result 45 that the desired symmetry of the mold is destroyed.

It is the principal object of the present 50 invention to provide in association with a mold of the above described character,

simple, practical and efficient means to lock the side pieces of the mold against displacement whereby to insure their rigidity while the end pieces of the mold are being cast.

A further object of the invention resides 60 in constructing the locking means so as to be adjustable to fit molds of different sizes and proportions.

An embodiment of the invention has been 65 illustrated in the accompanying drawings in which like parts are correspondingly indicated throughout the views and in which

Figure 1 represents a plan view of the unfinished mold in its condition for casting the end members of the same, showing the 70 locking appliance of the present invention in its operative position,

Figure 2, a section taken on the line 2—2, Figure 1, and

Figure 3, a fragmentary end view looking 75 in the direction of the arrow A in Figure 2.

Referring to the drawings, the reference character 5 designates a table or work bench upon which the mold is supported. The mold comprises a base member 6 and side 80 members 7 made by the hereinbefore described methods.

The base member has a face of fanciful 85 form for the production of building blocks of ornamental design and the side members have at their edges, tongues 7a which fit in correspondingly formed grooves 6a of the base member.

The side members 7 extend in parallel 90 relation to each other at right angles to the base member and in order to cast the end members which when the mold is completed rests upon the ends of the base member and extend between the ends of the side members, forms are made by the instrumentality 95 of upright boards or plates 9 placed against the end surfaces of the base and side members, and metal partitions 10 placed between the side members parallel to the plates and at a distance therefrom equal to the desired thickness of the end members of the mold. These partitions may be made 100 lengthwise expansible for their adaptation to molds of different sizes and they are supported by vertical legs or squares 12 upon 105 the upper surface of the base member.

In the construction shown in the drawings, the partitions are composed of a middle section 14 consisting of two plates connected by bolts 13, and end sections 15 which are 110

clamped between the plates of the middle section are provided with channelled flanges for their connection with the upright squares.

5 It is to be understood that the specific construction of the members so far described is not a part of the present invention.

10 The locking means involved in the invention comprises a standard 16 fastened in an upright position at a side of the table or work bench 5 by means of a headed bolt 17 and a nut 18 screwed upon the threaded end thereof. The bolt may be secured beneath the top of the bench or table by passing it 15 through alined holes in opposite cleats thereof and the lower end of the standard may be inserted in a socket of a support 19 upon which the bench or table stands. The nut 18 on the bolt is screwed against the standard to hold it in position.

20 Slidably mounted on the standard is a sleeve 20 which carries a horizontally projecting arm 21. The arm extends across the mold above the side members 7 thereof 25 and it carries a plurality of sliding stops 22 which are each provided with a set screw 23 to secure them in their adjusted positions on the arm. One of the stops cooperates with the portion of the sleeve 20 below the 30 arm 21 to clamp the side member of the mold nearest the standard against lateral movement and two other stops engage at opposite sides of the other side member of the mold and thus perform a similar function 35 with relation thereto.

It will be apparent that the attachment, 40 as shown and described, provides a simple means for locking the side members of the mold in their upright position and against lateral displacement, that the sliding sleeve and the sliding stops provide an adjustment to fit the device to molds of different sizes and proportions, and that if the service of the appliance is not desired, the entire device 45 may be moved out of the way without detaching it from the table or work bench on which the mold is supported.

Variations in the construction and arrangement of the parts of the appliance may 50 be availed of within the scope of the invention.

Having thus described my invention, what

I claim and desire to secure by Letters Patent is:—

1. A holding appliance for mold members comprising in combination with a support for the mold, a standard on the support, an arm projecting laterally from the standard, and stops on the arm for engagement with members of a mold on the support. 60

2. A holding appliance for mold members comprising in combination with a support for the mold, a standard on the support, a laterally projecting arm slidable on the support, and adjustable stops on the arm for engagement with members of a mold on the support. 65

3. A holding appliance for mold members comprising in combination with a support for the mold, a standard on the support, an arm projecting laterally from the standard, sliding stops on the arm for engagement with members of a mold on the support, and means to secure the stops in adjusted positions. 70

4. A holding appliance for mold members comprising in combination with a support for the mold, a standard on the support, a laterally projecting arm slidable on the support, sliding stops on the arm for engagement with members of a mold on the support, and set screws to secure the stops in adjusted positions. 75

5. A holding appliance for mold members comprising in combination with a support for the mold, a bolt on the support beneath the top thereof, a standard having an aperture through which the bolt projects, a nut on the bolt, securing the standard, an arm projecting laterally from the standard, and stops on the arm for engagement with members of a mold on the support. 80

6. A holding appliance for mold members comprising in combination with a support for the mold, a standard on the support, a sleeve on the standard, a laterally projecting arm carried by the sleeve, a stop on the arm cooperating with the sleeve to hold a member of a mold on the support against lateral displacement, and stops on the arm to 100 similarly hold another member of the mold. 85

In testimony whereof I have affixed my signature.

ERNEST S. NIESTRADT.
